(57) **CLAIM**

I claim the ornamental design for a fishing light, as shown and described.

DESCRIPTION

FIG. 1 is a perspective view of a fishing light, showing my new design;

FIG. 2 is a front elevational view thereof the rear elevational view being a mirror image thereof;

FIG. 3 is a left-side elevational view thereof;

FIG. 4 is a right-side elevational view thereof;

FIG. 5 is a top plan view thereof; and,

FIG. 6 is a bottom plan view thereof.

The broken lines showing a power cord depict environmental matter and form no part of the claimed design. The remaining broken lines depict portions of the fishing light that form no part of the claimed design.

1 Claim, 4 Drawing Sheets(56)
